UNITED STATES PATENT OFFICE.

JOHN H. HOWARTH, JR., OF NEW HAVEN, CONNECTICUT.

LEGGIN.

SPECIFICATION forming part of Letters Patent No. 292,819, dated February 5, 1884.

Application filed September 24, 1883. (No model.)

To all whom it may concern:

Be it known that I, JOHN H. HOWARTH, Jr., of New Haven, in the county of New Haven and State of Connecticut, have invented 5 a new Improvement in Leggins; and I do hereby declare the following, when taken in connection with accompanying drawings and the letters of reference marked thereon, to be a full, clear, and exact description of the same, 10 and which said drawings constitute part of this specification, and represent, in—

Figure 1, a side view of the leggin as applied to the leg; Fig. 2, a side view of the leggin removed; Fig. 3, the spring detached, the 15 last two figures enlarged.

This invention relates to an improvement in leggins which are made open at one side and provided with devices for securing the two edges together. In previous constructions the 20 two edges have been provided sometimes with buttons and button-holes, sometimes with buckles and straps, and sometimes with lacings. In securing the leggin upon the leg considerable annoyance is experienced from the 25 fact that, owing to the flexibility of the material of which the leggins are made, the upper part falls down around the ankle and interferes with securing. This is particularly the case where the securing device is a lacing arranged to engage lacing studs or hooks on the 30 two parts. The person applying them is obliged to hold the upper part of the leggin while the lower part is being laced, as the lacing must necessarily commence at the bottom.

The object of my invention is to overcome 35 this difficulty; and it consists in providing the upper part of the leggin with a spring encircling that portion, and so as to embrace the leg and hold the top of the leggin fast 40 around the leg of the wearer, and so that the whole line of studs will be readily exposed for lacing and without interference from the upper part of the leggin, and as more fully hereinafter described, and particularly recited 45 in the claims.

The cut of the material to form the leggin A is the same as in the usual construction. Around the upper end of the leggin I introduce a spring, B. This spring is best made, 50 as seen in Fig. 3, of ring shape divided, the diameter of the ring being somewhat smaller than the calf of the leg, and so as to require

some little expansion to embrace the leg. The two ends of the ring are turned downward to form vertical stays or springs C D. This 55 spring is best made from steel wire bent to this required shape. The spring is introduced between the two thicknesses of the leggin, the ring being at the top, the two stays D C extending down in each edge of the leggin, as 60 indicated in broken lines, Fig. 2. The stays D C of the spring serve to stiffen the upper portion, and so that the lacing-studs a need only extend up nearly to the ends of the stays C D of the spring, as seen in Figs. 1 and 2. 65 The lacing and lacing-studs are applied in the usual manner for applying such fastenings to leggins and like articles.

In placing the leggin on the leg the upper part is drawn on to about the required position and the spring permitted to contract to embrace the leg, and thus support the leggin, leaving the edges below exposed and without any liability of the upper part falling down to interfere with lacing up. 70

While the stays D C avoid the necessity of extending the lacing-studs to the top of the leggin, the studs may be so arranged, if desired; but in case the lacing is desired to the extreme top of the leggin, the stays D C may 75 be dispensed with and simply the divided ring-shaped spring introduced.

The ring-shaped spring, with the stays D C, may be made as an article of manufacture and sold to the trade to be introduced in the process of manufacturing the leggin. 85

By employing the divided spring at the upper end of the leggin, as described, the same leggin may fit various-sized legs, so that a less number of sizes may be kept in stock by the 90 dealer.

I am aware that leggins have been constructed with divided rings, one introduced at the upper end, the other down upon the leg, and the two connected by rods; but such construction I do not claim, the essential feature of my invention being a single divided ring at the top, having its two ends turned downward to form vertical stays or springs within the leggin, the extreme ends of said stays or springs 95 unconnected.

I claim—

1. The herein-described spring for leggins, consisting of the divided ring-shaped spring 100

B, with the stays D C, extending, respectively, from the ends of the spring, the ends of said stays free or disconnected, substantially as described.

5 2. A leggin open at the side, having a divided ring-shaped spring, B, introduced at its upper end, and with stays D C, extending from the respective ends of the spring down the edges of the leggin, the ends of said stays dis-

connected except by the material of the leggin itself, combined with lacing devices on the two sides extending from the bottom upward to near the ends of the stays, substantially as described.

J. H. HOWARTH, JR.
